Primary Examiner — Karen S Acker*Assistant Examiner* — Steven B Reinholdt, Jr.(74) *Attorney, Agent, or Firm* — Amardeep S. Grewal; Gerard M. Donovan; Reed Smith LLP(57) **CLAIM**

The ornamental design for a beverage container closure, as shown and described.

DESCRIPTION

FIG. 1 is a perspective view of a beverage container closure showing the design.

FIG. 2 is a side elevation view of the beverage container closure of FIG. 1.

FIG. 3 is another side elevation view of the beverage container closure of FIG. 1.

FIG. 4 is another side elevation view of the beverage container closure of FIG. 1.

FIG. 5 is another side elevation view of the beverage container closure of FIG. 1.

FIG. 6 is a top plan view of the beverage container closure of FIG. 1.

FIG. 7 is a bottom plan view of the beverage container closure of FIG. 1; and,

FIG. 8 is another perspective view of the beverage container closure of FIG. 1.

The dashed lines and the area within them shown in the drawings illustrate portions of the beverage container closure that form no part of the claimed design. The shading lines shown in the drawings represent the approximate three-dimensional contour of the claimed design and are not intended to indicate surface decoration.
